UNITED STATES PATENT OFFICE.

WILLIAM P. GREINER, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA.

AUTOMATIC DRYING MACHINE.

Application filed December 5, 1924, Serial No. 754,111. Renewed August 31, 1927.

This invention relates to drying machines and it has more particular reference to that type comprising an enclosure through which article-carriers are progressed with capacity for periodic "ejection" and "entry" to permit removal of dried articles and their replacement by others to be similarly treated. Drying machines of the typified character while more or less effective for the objects had in view are open to criticism on economical and constructive lines, and I have found that in order to secure maximum efficiency such a machine should embody certain fundamental characteristics, to wit: During the drying process the article-carriers should be close enough and in relative position so as not to require too large a drying enclosure. When in "stripping" and "clothing" position, the article-carriers should be so located so that they can be stripped and clothed, or turned for inspection without interfering with the adjacent ones. Again the article-carriers should be capable of satisfactory and practical transfer from the drying to the "stripping" and "clothing" positions, and back again into drying location. Such satisfactory and practical movements of the article-carriers should be uniform and steady while not too quick, thereby avoiding any waiting periods on the part of the operator or operators for presentation of said carriers.

With the noted desiderata in view I have devised a drying machine primarily characterized by novel gyrating means, positively functional to also selectively enter and eject non-consecutive article-carriers by *extensil-retractil* action along direct radial lines. Hereinafter in the descriptive matter and claims it is to be understood that the term *selectively*, as applied to the article carriers and associated parts, means "non-consecutive" ones; or, those separated by more than one regular interval. Another object attained by my improvements is the provision of a continuously acting machine characterized by the fact that each individual article-carrier is gyrated around the drying zone more than once intermediate its entry and ejection; or, after clothing and prior to stripping, respectively.

Other objects associated with this invention are to ensure more expeditious "clothing," "stripping" and "inspection" of the

article-carriers while exterior of the drying zone; to efficiently circulate the drying medium; generally augment the machine capacity; and to provide a relatively cheap and compact structure for the attainment of the several objects had in view.

Of the various embodiments of which this invention is capable I have selected for illustration and specific description herein, one which at the present time is believed to exhibit said invention in a most convenient, compact and effective form. This embodiment is shown by the accompanying drawings, wherein corresponding parts are designated by the same reference characters in all the views, while the novel features are tersely stated by the appended claims.

In the drawings:

Fig. I is a top plan view of an automatic drying machine embodying the herein set forth improvements.

Fig. II is a front elevational view of the same.

Fig. III is a vertical section taken approximately as indicated by the arrows III—III in Fig. I.

Fig. IV is, somewhat enlarged, horizontal section taken substantially on the plane indicated by the arrows IV—IV in Fig. III.

Fig. V is a fragmentary vertical section taken through the machine, on the plane indicated by the arrows V—V in Fig. IV.

Fig. VI is a detail plan view of the cam mechanism effective to eject and re-enter the article-carriers, and hereinafter more fully described.

Fig. VII is a vertical section taken at right angles to Fig. IV, as indicated by the arrows VII—VII thereon.

Fig. VIII is a fragmentary plan view of a spider or planetary gyrator that supports the radially movable article carrier instrumentalities.

Fig. IX is a sectional view taken as indicated by the arrows IX—IX on Fig. IV.

Fig. X is a fragmentary plan view of an aligning mechanism, hereinafter more fully explained; and,

Fig. XI is a detail view of certain turning instrumentalities later on described in detail.

In carrying out this invention in accordance with the organization illustrated, it

will be seen that I construct an enclosure 1 of thermo-insulated sheets 2, and standard sections 3, the same being generally rectangular in plan with an offset-bellied; 5 frontal portion 4. This enclosure 1, is conveniently supported at an elevation above floor level by standard section verticals 5, braced by similar section transverse members 6, so as to afford space to accommodate 10 certain mechanism hereafter fully described.

Referring more particularly to Figs. II, II and IV, it will be seen that the frontal bellied portion 4 aforesaid has its upper part inwardly inclined at 7 for a purpose later on 15 referred to, while the enclosure 1 is subdivided by a vertical partition 8 to afford a space 9, housing a bank of heating coils 9' with an exhaust outlet 1' in any convenient location. Transversely of the coil space 9 20 is a substantially conical air conduit 10, the inner smaller end whereof is located concentric with a housing 11, for the vertically rotatable fan 12, journaled in bearings 13 mounted in said conduit 10. Rotary motion 25 is imparted to the fan 12 by direct drive from an electric motor 14—for example—conveniently mounted at the back of the enclosure 1 upon a skeleton support 15, of standard sections, braced by similar section 30 inclined struts 16.

The vertical partition 8, above referred to, also sets apart a portion of the enclosure 1 that constitutes the drying zone 17, and it will be seen there is provided in the upper 35 part of said zone a laterally disposed baffle 18 having a pendent substantially conical hood 19 at frontal portion. This hood 19, it is to be noted, is supported concentrically above a rotary spider or planetary-gyrator 20 later on fully described. At this juncture, however, it is to be observed that the lateral baffle 18 and pendent hood 19 jointly define a path of circulation for the drying medium, as indicated by the arrows appearing 40 in Fig. III, whereby the cubic content of the drying zone is reduced to a minimum, consistent with proper clearance for the article-carriers 21, during passage therethrough.

Referring again to the rotary spider or planetary gyrator 20, the same is of dished cross-section with a central hub 22 by means of which it is mounted on a sleeve 23, in turn rotatable about a vertical journal post 24 50 supported in a foot-step bearing 25 integral within the gear box, comprehensively designated by the numeral 26. Relative movement of the spider or gyrator 20 and sleeve 23 is effectively prevented by means of a lock pin 27 in the well known way, while said sleeve is supported on the foot-step 25 with interposition of a thrust collar bearing 28; whereas a fixed collar 29 counteracts any lifting tendency under centrifugal action as 55 well as ensuring correct adjustment of the

respective parts. The journal post 24 is secured in the foot-step 25 by means of a lock stud 30 and a taper drift pin 31, as will be readily understood by those conversant with the art.

Attention is directed to the fact that the aforesaid sleeve 23 is provided with a worm wheel 32 at or near its lower end—conveniently integral therewith—which meshes with a worm drive 33 on a horizontal shaft 70 75 34, journaled in cap bearings 35 rigidly attached in opposed relation through apertures 36 in the walls of the above referred to gear box 26, and locked in place by means of tap bolts 37. Rotary motion is imparted to 80 the shaft 34, through the medium of a worm wheel 38—rigidly attached thereon—meshing with a worm drive 39 on a second horizontal shaft 40 journaled in a tubular bearing 41, 85 removably secured by tap bolts 42 in an aperture 43 of the gear box 26. Longitudinal displacement of the shaft 40 relative to the bearing 41 is obviated through the medium of fixed and removable collars 44, 45, respectively, as will be readily understood. Seepage 90 of lubricant outwards from the bearing 41 is prevented by means of a coupler 46 conveniently screw-threaded on to the shoul- 95 dered end 47 of said bearing. This coupler 46 is formed at its outer end to accommodate packing 48, appropriately held in place by a gland 49 and screw studs 50, in the well known way. The horizontal shaft 40 aforesaid is journaled at its outer end in a bearing 51 mounted on a transverse brace 52 in the 100 sub-structure of the drying machine, and it is conveniently fitted with a coned pulley 53 co-ordinated by belt drive 54 with a similar pulley 55 on the fan shaft 56 directly driven by the motor 14, whereby provision 105 is made for variable rotation of said shaft 40.

Keyed or otherwise immovably mounted on the shaft 34 is a cam device 57 the active part 58 whereof cooperates with freely-rotatable anti-friction rollers 59, supported by 110 studs 60, at the underside of a horizontally reciprocable push bar 61, provided with an angularly directed toe portions 62 at each end thereof. This push bar 61 is conveniently of rectangular cross section, and it is supported by and movable in guides 63, 63 laterally projecting in opposed relation from the gear box 26.

Mounted on, and attached by bolts 64 to, the gear box 26, is a circular cap-plate 65 120 having a peripheral flange 66 with opposed notches 67, 68 for a purpose later on again referred to, and a longitudinal slot 69 which accommodates the heads of the studs 60 and thereby permits free reciprocation of 125 the push bar 61.

Referring again to the rotary spider or planetary-gyrator 20, it is formed with a series of radial grooves 70 for the article-carrier supporting-members 71, each of 130

which is provided with two notches 72, 72' in its underside for engagement over the peripheral flange 66 of the cap-plate 65; and, obviously, anti-friction means—not shown—may be associated in the radial grooves 70 to facilitate easy reciprocation of the members 71. Hereinafter the members 71 will be specifically designated as "thrust-bars" for the sake of brevity and to specifically define their function over analogous means. An appropriate annular closure 73 is securely attached on the spider or planetary-gyrator 20 to complete proper telescopic guidance for, as well as prevent radial deflection of the thrust bars 71, and said closure is provided with a lateral flange 74 having peripheral notches 75 in register above said thrust bars, for a purpose hereafter explained. The spider or gyrator 20 may conveniently be closed in by means of a sheet metal cover 76 suitably attached to the closure cap 73 in any of the well known ways.

Each article-carrier 21 is removably attached to a holder 77 having a pivot-shank 78 and integral toothed part 79 (Fig. V) for cooperation with the complementarily configured hub 80 of a bearing bracket 81 conveniently secured by bolts or the like 82 to the outer free end of each above referred to extensil-retractil thrust-bars 71. Each aforesaid holder 77 is under the action of a compression spring 83, and is further provided with a pair of diametrically opposed laterally projecting upper lugs 84, and a lower lug 85 disposed at an angle of ninety-degrees relative thereto. These lugs 84, 85, serve to effect automatic turning of the forms 21 by cooperation with certain instrumentalities later on explained; while each bearing bracket 81 is provided with a foot piece 86 for engagement by either one or the other of vertically adjustable studs 87, one of which is secured in each angular toe 62 of the push bar 61 by means of lock nuts 88.

In operation, and assuming the machine is—as shown—designed for drying hosiery, while for explanatory purposes let it be further assumed that all the extensil-retractil thrust bars 71 are inwards relative to the rotary spider or planetary-gyrator 20, and consequently all the article-carriers 21 within the drying zone 17. Upon starting the motor 14, it will be obvious that rotary motion will be imparted through shaft 36 to the fan 32, and through the co-ordinating drives, hereinbefore described, to shafts 40 and 34. Rotation of the shaft 34 with a continuous uniform action—indicated by the arrow in Fig. VII—will revolve the spider or planetary gyrator 20 in a counter-clockwise direction. At the same time the cam device 57, rotating with the shaft 34, will by virtue of the active portion 58 thereof co-operating with the anti-friction rollers

59, slide the push bar 61 to the left-hand—as best understood from Figs. IV-IV—whereupon the stud 87, at the advancing end of said bar, will engage the foot piece 86 and thrust an article-carrier 21 to the position designated *a* in Fig. IV. It will, of course, be readily understood that the floor of the enclosure 1, is slotted at 89 to accommodate the movement just described. Continued rotation of the spider or planetary-gyrator 20 and forward progression of the holder 77 advances the upper lugs 84, into engagement with a suitable tripper 90 to effect proper turning of the carrier 21 through an angle of ninety degrees, or in the direction of the raceway 91, until it emerges through the slot 92 into position *b* read for the stripper. As the holder 77 is emerging from out of the drying zone 17 through the slot 92 one of the upper lugs 84 thereof will engage below the overhang 93 of a substantially Z-shaped arcuate member 94—Figs. IV and IX—that serves to effectively prevent any lifting tendency during the "stripping" operation, and which would otherwise occur due to natural upward pull incident to removal of the dried article. After leaving the arcuate member 94 the carrier 21 may be freely turned about its pivot shank 78, re-clothed and inspected before arriving at the position designated *c* on Fig. IV. At this location, and in order that the carrier 21 shall re-enter the drying zone 17 with properly aligned directional travel, I provide a slideable trip 95 under the action of a spring 96 and limited in travel by a pin 97 engaged in a slot 98 thereof. This trip 95 engages either of the upper lugs 84 and automatically turns the holder 77 into proper alignment, as will be fully understood by those acquainted with the art. Further progression of the carrier 21 advances the same through the entry slot 99 of the enclosure 1, to position *d* and from thence into contact with suitable trippers 100 which effect a quarter turn of said form into radial position relative to the spider or planetary-gyrator 20, for inward retraction via a return slot 101 to position marked *e* by aid of the cam device 57 and associated means, hereinbefore fully described.

Particular attention is here directed to the fact that the cam device 57 is configured with a dwell section *a'* and that it is geared relative to the spider or planetary-gyrator 20 so that when the stud 87 ejects a thrust bar 71 and its sustained article-carrier 21, it will move back and miss the next two holders 77 and so on; or, any other desired non-consecutive section may—obviously—be easily arranged for by appropriate gearing. When sufficient carriers 21 are ejected—as shown—so that one has arrived at the location designated *d*, continued rotation of the spider 130

or planetary-gyror 20 will effect transfer of said carrier to position "e", or into drying position. It is to be noted that ejection and retraction of non-consecutive carriers 21 5 synchronize, or take place concurrently. In practice the carriers 21 will always occupy the position--toe inwards--shown during progress through the drying zone 17.

Attention is also especially drawn to the 10 cooperative relation existing between the thrust bars 71 and the peripheral flange 66 of the cap-plate 65, it being clearly understandable that when the inner notches 72 of the thrust bars 71 engage the flange 66 they 15 retain said bars in extended position. On the other hand, when the outer notches 72 similarly engage the flange 66 the thrust bars 71 are retained in retracted position during progress through the drying zone 17 while 20 the notches 67, 68, respectively, accommodate simultaneous extension and retraction of said bars, as hereinbefore explained. Thus it will be readily acknowledged that the thrust-bars 71 and associated carriers 21 are effectively 25 prevented from displacement, otherwise than as provided for, during the "stripping," "re-clothing" and "inspection" periods.

In the particular embodiment of the invention illustrated every third carrier 21 is 30 acted upon, so that by arranging the total number of such carriers in the machine to be one less than a multiple of the number three (in this case thirty-five) each said carrier will be moved in proper sequence. In other 35 words every third carrier 21 is ejected from the enclosure 1, while each said carrier will pass through the drying zone 17 two full revolutions of the spider or planetary-gyror 20, and will be moved into the stripping 40 position "b" at the end of the third revolution.

From the foregoing it is thought that the simple and practical phases embraced in the 45 illustrated construction will be clearly appreciated, and that it is designed to accomplish, among others, all of the objects and advantages set forth. Again, without further comment, the foregoing detailed description fully reveals the gist of the invention, so that others can, by applying common 50 knowledge, readily adapt it for various uses without omitting certain features that, from the standpoint of prior art, fairly constitute essential characteristics of the generic 55 aspects thereof. Therefore, all such other applications or adaptations should, and are intended to, be comprehended within the meaning and range of equivalency circumscribed by reasonable interpretation accorded 60 the subjoined claims.

Having thus described my invention, I claim:

1. A drying machine embodying a moisture exhausting zone, form carriers progressive therethrough, and means for selectively 65

ejecting and entering non-consecutive form carriers to effect stripping and after reclothing respectively.

2. A drying machine embodying a moisture exhausting zone, form carriers continuously progressive therethrough, and means functional to simultaneously eject and enter selected non-consecutive form carriers for stripping and clothing respectively. 70

3. A drying machine embodying a moisture exhausting zone, form carriers progressive therethrough, and reciprocable means effective to radially eject and enter non-consecutive form carriers, whereby each consecutive form is caused to traverse the 75 exhausting zone more than once. 80

4. A drying machine embodying a moisture exhausting zone, form carriers continuously progressive therethrough, and means to selectively eject and enter non-consecutive 85 form carriers whereby adequate spacial relation obtain to effect stripping, clothing and inspection, of the articles treated.

5. A drying machine embodying a moisture exhausting zone, form carriers continuously progressive therethrough, and means operative to selectively reciprocate non-consecutive form carriers to eject and enter the 90 forms for stripping and after clothing.

6. A drying machine embodying a moisture exhausting zone, radially reciprocable form carriers continuously progressive therethrough, and means for ejecting and entering non-consecutive form carriers to effect stripping and clothing of the forms, respectively. 95

7. A drying machine embodying a moisture exhausting zone, radially reciprocable form carriers continuously progressive therethrough, means for ejecting and entering non-consecutive form carriers to effect stripping and clothing of the forms respectively, 100 and means for arresting said carriers in extended and retracted position.

8. A drying machine embodying a moisture exhausting zone, a conveyor thereunder, 105 form carriers radially reciprocable in the conveyor, means operative to selectively extend and retract non-consecutive carriers, and means for continuously rotating the aforesaid conveyor. 115

9. A drying machine embodying a moisture exhausting zone, a conveyor thereunder, form carriers radially reciprocable in the conveyor, means operative to selectively extend and retract non-consecutive carriers, 120 means for continuously rotating the aforesaid conveyor, and means effective to retain extended and retracted carriers against relative displacement.

10. A drying machine embodying a moisture exhausting zone, a conveyor thereunder, form carriers radially reciprocable in the conveyor, means operative to selectively extend and retract non-consecutive carriers, 125 means for continuously rotating the aforesaid conveyor, and means for continuously rotating the afore- 130

- 5 said conveyor, and means effective to retain extended and retracted carriers against relative displacement, said means comprising an annular member co-operative with notches at the under side of the form carriers, and said member having intervals accommodating reciprocation of the form carriers.
11. A drying machine embodying a moisture exhausting zone, a planetary-gyrator thereunder, form carriers radially reciprocable in the planetary-gyrator, means operative to selectively extend and retract non-consecutive carriers, means for continuously rotating the aforesaid planetary-gyrator, means effective to retain extended and retracted carriers against relative displacement, said means comprising an annular member co-operative with notches at the underside of the form carriers, said annular member having intervals to accommodate reciprocation of the form carriers, and means effective to impart a quarter-turn to each form after leaving—and prior to entering—the drying zone to ensure uniform directional progression therethrough. 70
12. A drying machine embodying a moisture exhausting zone, a spider thereunder, form carriers radially reciprocable in the spider, means operative to selectively extend and retract non-consecutive carriers, means for continuously rotating the aforesaid spider, means effective to retain the extended and retracted carriers against relative displacement, and means functional to automatically effect proper directional placement of each form for ejection from—and entry into—the machine. 80
13. A drying machine embodying a moisture exhausting zone, a spider thereunder, form carriers radially reciprocable in the spider, means operative to selectively extend and retract non-consecutive carriers, means for continuously rotating the aforesaid spider, an annular member co-operative with notches at the under side of the carriers to arrest the same in extended and retracted position, said member having intervals to accommodate reciprocation of the carriers, means functional to impart a quarter-turn to each form after leaving—and prior to entering—the drying zone to ensure uniform directional progression therethrough, and means operative to automatically effect proper directional placement of each form for entry into the machine. 90
14. In a drying machine embodying a moisture exhausting zone, the combination of a spider having a series of reciprocable radii supporting clothable forms, means for selectively extending and retracting non-consecutive radii, and means for continuously rotating the aforesaid spider. 105
15. In a drying machine embodying a moisture exhausting zone, the combination of a spider having a series of radial thrust bars supporting clothable forms, a transfer device effective to selectively extend and retract non-consecutive thrust bars, and means for continuously rotating the aforesaid spider while intermittently reciprocating the transfer device. 115
16. A drying machine comprising an enclosure subdivided to provide heating and moisture exhausting zones, means within the moisture exhausting zone defining a looped path of circulation for the drying medium, means for continuously progressing article-carrying forms therethrough, and means for selectively ejecting and entering non-consecutive forms for stripping and clothing. 125
17. A drying machine comprising an enclosure subdivided to provide heating and moisture exhausting zones, a baffle and pendent-hood in the moisture exhausting zone defining a looped path of circulation for the drying medium, means for continuously progressing article carrying forms through the drying zone, and means for selectively ejecting and entering non-consecutive forms for stripping and clothing. 130
18. A drying machine comprising an enclosure subdivided to provide heating and moisture exhausting zones, a baffle and pendent-hood in the moisture exhausting zone defining a looped path of circulation for the drying medium, means for continuously progressing article carrying forms through the drying zone, means for selectively ejecting and entering non-consecutive forms for stripping and clothing, and means ensuring uniform directional entry of the aforesaid forms into the enclosure. 140
19. A drying machine comprising an enclosure subdivided to provide heating and moisture exhausting zones, a baffle and pendent-hood in the moisture exhausting zone defining a looped path of circulation for the drying medium, means for continuously progressing article-carrying forms through the drying zone, means for selectively ejecting and entering non-consecutive forms for stripping and clothing, means ensuring uniform directional entry of the aforesaid forms into the enclosure, and means effective to impart a quarter-turn to the forms for exit and entry relative to the aforesaid moisture exhausting zone. 150
20. A drying machine comprising an enclosure subdivided to provide heating and moisture exhausting zones, a baffle and pendent-hood in the moisture exhausting zone defining a looped path of circulation for the drying medium, means for continuously progressing article-carrying forms through the drying zone, means for selectively ejecting and entering non-consecutive forms for stripping and clothing, means ensuring uniform directional entry of the aforesaid forms into the enclosure, means effective to impart a quarter-turn to the forms for exit and entry relative to the aforesaid moisture exhausting zone. 160

entry relative to the moisture exhausting zone, and means preventing displacement of the forms when in extended and retracted position.

5 21. A drying machine with a moisture exhausting zone, article-carriers progressive about said zone, and means adapted to selectively thrust non-consecutive article-carriers horizontal relative thereto to effect application and removal of the articles treated.

10 22. A drying machine with a moisture exhausting zone, reciprocable article-carriers progressive about said zone, and means selectively thrusting non-consecutive carriers horizontally by extensil-retractil action relative to said zone for application and removal of the articles treated.

15 23. A drying machine with a moisture exhausting zone, reciprocable article-carriers progressive about said zone, means selectively thrusting non-consecutive carriers horizontally by direct extensil-retractil action relative to said zone for application and removal of the articles treated, and

20 25 means temporarily arresting the article-carriers in entered or expelled position.

25 24. A drying machine with a moisture exhausting zone, a rotor thereunder, article-carriers radially movable relative to the rotor, means adapted to selectively thrust non-consecutive carriers horizontally along direct-radial lines with respect to said zone for application and removal of the articles treated, and means temporarily restraining

30 35 the carriers at the thrust limits.

25. A drying machine with a moisture

exhausting zone, a planetary gyrorotor thereunder, members radially reciprocable in the gyrorotor and bearing clotheable supports, means intermittently thrusting non-consecutive article carriers to enter and expel the sustained supports relative to the machine, means continuously revolving the gyrorotor about its axis, and means temporarily arresting the carriers at the thrust limits.

30 26. A drying machine with a moisture exhausting zone, a planetary rotor thereunder, members radially reciprocable in the rotor and bearing clotheable supports, means intermittently thrusting non-consecutive article carriers to enter and expel the sustained supports relative to the machine, means continuously revolving the rotor about its axis, and means temporarily arresting the carriers at the thrust limits.

35 27. A drying machine with a moisture exhausting zone; a planetary rotor thereunder; members radially reciprocable in the rotor and bearing clotheable supports; means intermittently thrusting non-consecutive article carriers to enter and expel the sustained supports relative to the machine; means continuously revolving the rotor about said axis; means temporarily arresting the carriers at the thrust limits; and individual impact devices that serve to automatically move each clotheable support into proper direction for entry into, progression about, and expulsion from the machine.

In testimony whereof, I have hereunto signed by name at Philadelphia, Pennsylvania, this 3rd day of December, 1924.

WILLIAM P. GREINER
